United States Patent Office

Des. 181,882
Patented Jan. 7, 1958

181,882

LAWN SPRINKLER

Laddie J. Sebek, Hinsdale, Ill., assignor to Central Die Casting and Manufacturing Company, Inc., Chicago, Ill., a corporation of Illinois

Application April 22, 1957, Serial No. 45,834

Term of patent 14 years

(Cl. D91—1)

FIG. 1

FIG. 2

Figure 1 is a perspective view of a lawn sprinkler showing my new design; and

Figure 2 is an enlarged rear end elevational view of Figure 1.

I claim:

The ornamental design for a lawn sprinkler, substantially as shown.
